WILL H. BORROW, OF SEATTLE, WASHINGTON.

SHIP-VENTILATOR CLOSING AND OPENING MECHANISM.

Application filed November 3, 1921. Serial No. 512,465.

My invention relates to mechanism for closing and opening ventilators of a ship.

It is absolutely essential that the hold of a ship be provided with ventilators. Otherwise many types of cargo will be destroyed, to say nothing of the absolute necessity of providing such ventilation for the ship's crew and others who may be located below deck. To this end, pipes with large cowls 10 are mounted above deck. When a storm breaks the ends of these pipes must be closed to prevent water from passing directly down the same to the hold of the ship.

In effecting the closing of these pipes, the common practice is to place a cover over the same and securely lash a piece of canvas over this cover—said pipes having no other means for closing. Since an ordinary cargo ship has as many as thirty to sixty of 20 these vents, manifestly, it is a task which requires a great deal of time to accomplish and requires a considerable number of the ship's crew, whose services under such circumstances may be most advantageously employed otherwise.

A cover of metal has been suggested which is permitted to hang on a hook provided within the cowl when the ventilator is in open position. Upon the approach of 30 a storm, this metal cover is removed and placed upon the end of the ventilator's coaming or easing and clamped in position, much after the manner of the porthole windows or much as the covers of steam cookers are clamped into position,—each cover having a plurality of clamping mechanisms. The objection to this means of closing the 35 ventilator openings is that the covers for such purposes weigh normally as much as one hundred pounds and often more and it is manifestly no small task therefore in the case of a rolling and pitching vessel for the operator to lift off this heavy cover from its hook and place the same in position for 40 clamping, and then proceed to clamp the same. All of which requires considerable time since the operator must move into clamping position each of the clamping mechanisms of the cover after positioning 45 the cover.

Another means has been suggested for closing the said vent openings consisting of a cover hingedly mounted inside and on the

rear side of the cowl and sloping forward so that water may be drained off. The objection to this form of means is that in case of the breaking off of the cowl, there is no protection afforded against the inrush of water.

The importance of the shortness of time 55 which is required to open and close any mechanism of the character under consideration will be manifest from the following: The vessel's walls are of steel and very openly exposed to changes in temperature 60 so that a condensation of the moisture of the air, commonly known as "sweating" occurs on the vessel's walls on the inside of the vessel with the result that the walls become very damp and water appears on said 65 walls in the form of large globules much after the manner of refrigerator walls. Many classes of cargo, particularly grain, are quickly ruined and their value greatly 70 depreciated owing to this dampness arising 75 from the condensation occurring on the walls of the vessel. This condition demands that advantage be taken of any temporary lull in a storm to ventilate and completely 80 change the air in the hold of the vessel. Hence, such task must be possible of accomplishment in a very short time, otherwise, the danger from inrushing water forbids taking advantage of said temporary lull in 85 the storm for ventilating purposes.

On the other hand the rapid closing of the pipe openings is manifestly equally important in the case of fire in the hold of the vessel. On such occasions the number of duties per member of the crew is so 90 great that the shortening of time required to accomplish any one of the duties adds greatly to the general security since it releases such member for service for an unexpected emergency. Promptly cutting off 95 the air, or "smoldering" the fire may be often the most efficient means of extinguishing the fire owing to its being located in places difficult of access.

In general, the objects of my invention is 100 to overcome these objections above noted. A primary object of my invention is to provide a mechanism for opening and closing the ventilator openings which consists of a cover maintained in position so that no lifting of the same is required or a cover which 105

is releasably secured and therefore guided during its manipulation into closed and open position and which may be quickly clamped into position by an operator. A further primary object of my invention is to provide such a ventilator closing and opening mechanism as may be utilized in connection with a cowl as normally found upon a ship and not interfere with the operation of said cowl while maintained within the coaming opening and which may be moved into closed position quickly and without any lifting on the part of the operator, and which is independent of said cowl. A further primary object of my invention is to provide such an opening and closing mechanism as may itself operate as a cowl when not disposed in closed position. Finally, a primary object of my invention is to provide a cover which may be clamped into final closed position by a single clamping member.

The above mentioned general objects of my invention together with others inherent in the same are attained by the mechanism illustrated in the following drawings, the same being merely preferred exemplary forms of embodiment of my invention, throughout which drawings like reference numerals indicate like parts:

Fig. 1 is a view in section of a ship ventilator closing and opening mechanism embodying my invention, illustrating the same in closed position;

Fig. 2 is a view of the same in elevation, illustrating the same in open position;

Fig. 3 is a view of the same in cross section on broken line 3, 3 of Fig. 2;

Fig. 4 is a view of a detail, that is, the clamping member of the same;

Fig. 5 is a view in reduced scale of a modified form of cowl specially adapted for operation in conjunction with my invention;

Fig. 6 is a view of a modified form of clamping member;

Fig. 7 is a view of a modified form of a ship ventilator closing and opening mechanism embodying my invention; and

Fig. 8 is a view of a modified form of a detail of the same.

In the end portion of a ship ventilator casting 9, an annular seat 10 is secured by riveting or otherwise. In this seat a packing groove 11 is located, preferably on the outer periphery of the upper side, and in this groove, packing 12 of suitable material, as rubber, preferably rectangular in form, is disposed.

A cover 13 is provided to fit upon said angular seat the outer edge 14 of which cover is preferably beveled so that it presents an extended bearing surface against the compressed packing 12, which compression occurs upon the cover being forced into final closing position as will be more fully hereinafter set forth. The cover 13, cross-sec-

tionally considered, is preferably of a crown form 15 about the center and a flat peripheral portion 16 is preferably of a width which will permit the same to be cut down to adapt said cover to be formed into varying sizes for different sized ventilators. Two depending lugs 17 are preferably provided on the under side of said cover, as well as a hole 18 axially disposed therethrough. These lugs have elongated openings 19. On top of the cover handles 20 are provided to be used in turning the cover when screwing the same down as hereinafter set forth.

In the said end portion of the ventilator under said cover, means to maintain said cover in open and closed position is provided consisting of a holding member 21, preferably a spider, which supports longitudinally of said end portion a sleeve 22, preferably threaded. In this sleeve 22 a worm 23 is positioned, one end of which is provided with a shoulder 24 and a tongue 25 disposed between said lugs 17 depending from said cover and in this tongue 25 a transverse opening 26 is placed. A clamping member 27 extends through the axially disposed hole 18 of said cover, the lower end 28 of which clamping member 27 is disposed in said transverse opening of said tongue 25. A pin 29 extending through said tongue 25 and said lower end of said clamping member 27 constitutes a pivotal connection between the said parts. A cam 30 with handle 31 is pivotally connected to said clamping member 27 by means of pin 32. A spring 33 urges the clamping member 27 downwardly. For convenience of manufacture I preferably form the upper portion of the worm 23 including the tongue 25 separately and secure the two parts together by a pin 34 which holds the worm fast in recess 35. For all purposes herein concerned said parts may be considered integrally formed. On one of the lugs 17 a snap 36 may be provided to project in small depression 37 in the tongue 25 to releasably hold the cover at various angles as respects the worm 23. A cowl 38 of conventional form may be positioned upon said upper end portion of the ventilator casting 9. A thumb nut 39 may be provided to clamp the cover in any desired position.

The modified form of cowl 40 shown in Fig. 5 may be slidably mounted upon said end portion of the ventilator casting, and when the ventilator opening and closing mechanism constituting my invention is in closed position, said modified form of cowl 40 could be dropped by releasing wing nut 41, to a position such that no portion of said cowl extends above the end of said ventilator casting so that danger of the cowl being broken off or injured in a heavy sea is greatly reduced.

Instead of the clamping member 27 hav-

ing a can means to clamp the cover tight, the upper end of said member as shown in Fig. 6 may be provided with threads 42 and a nut 43 with handle 44 provided to accomplish the final clamping operation.

A simplified form of my invention is illustrated in Fig. 7 wherein the cover 13 is secured to a rod 45 (herein said cover is illustrated as integrally and fixedly, as opposed to pivotally, formed with said rod) which is slidably disposed in a sleeve 46 having a longitudinal bayonet slot 47 provided therein. The bottom portion 48 of said slot is in the form of a spiral extending transversely of the sleeve while the upper portion 49 of said slot slopes downwardly to prevent a projection 50 carried by the rod 45 being jarred out of engagement therewith. A key 51 hingedly secured to the cover 13 functions to lock the cover 13 in closed position when said key is pushed into locking position in the recess 52 formed in the cover 13 and the annular seat 10.

In Fig. 8 a modified form of the upper end portion of the rod 45 is shown having a reduced portion 53 of square form slidably embraced by the lugs 54 of the cover 13 and with the threaded screw portion 55 on which a nut with handle similar to the nut 43 and handle 44 shown in Fig. 6 may be disposed.

The operation of the ship ventilator opening and closing mechanism embodying my invention is as follows:

When it is desired to close the ventilator, the operator need only reach in the open end of the cowl and depress the cover 13 into a horizontal position. A small sudden shove or blow will overcome the holding effect of the snap 36. Then by seizing the handle 20 the operator may screw down the cover into, or nearly into, contact with the packing 12. The steep pitch of the thread of the worm 23 permits this lowering part of the operation to be accomplished quickly. Then, pushing the handle 30 into horizontal position, operates to depress the cover, that is, to clamp it into final closed position as shown in Fig. 1; the beveled edge 14 forming a tight joint with the compressed packing 12; the material forming the exposed shoulder of said packing insuring a tight fit together with the pressure caused by the can 30.

In effecting this closing operation it will be noted that the operator has no lifting to do and that the cover is supported in all positions to be moved, without lifting, into such other positions as the occasion may require. The cover 13 may be turned into any desired position as the cowl is turned if desired. The projecting shoulder 24 limits the screwing down of the cover 13 so that there is no turning movement of the cover over the edges of the packing 12. The final clamping is achieved by a direct movement

downward of the cover upon the packing by operating the can 30 so that it presses down the cover 13. The elongated openings 19 in the lugs 17 permit said cover to move relative the worm 23 and the clamping member 27. The lugs 17 function in the capacity of a wrench as respects the tongue portion 25 of the worm 23 and are of great advantage although not indispensable. Manifestly since there is but one clamping member to be operated, the closing of the ventilator requires the minimum of time and no attention relative to proper positioning.

Obviously, a ventilator casing or combing provided with my opening and closing mechanism may dispense with a cowl altogether since the cover 13 itself may be disposed at the necessary angle to function as a deflector, for example, as shown in dotted line 56 in Fig. 2, the snap 36 serving to hold the cover in desired tilted position.

The modified form shown in Fig. 6 manifestly provides for the depressing of the cover 13 upon screwing down the nut 43 upon the threaded portion 42 of the clamping member 27.

In the modified form shown in Fig. 7 of a ship ventilator closing and opening mechanism, the cover 13, with its integrally formed rod 45 having projection 50, is lifted out of engagement with the upper portion of the slot 49 and the cover slightly turned to permit of its being allowed to move downwardly until the projection 50 engages the spiral portion 48 of the slot, when a small turning force applied through the handles 20 will cause the cover to engage tightly with the packing 12, whereupon the key 51 may be dropped into locking position and the cover 13 thus maintained in locked position. The lower portion of the slot 48 could extend directly transverse instead of spirally and the modified form of the cover 13 shown in Fig. 8 could be employed so that no turning motion as respects the packing 12 would follow.

Obviously, changes may be made in the form, dimensions, and arrangement of the parts of my invention, without departing from the principle thereof, the above setting forth only preferred forms of embodiment.

I claim:

1. A ship ventilator closing and opening mechanism embodying a cover; an annular seat provided on the end portion of the ventilator coaming to which the closing and opening mechanism is applied; cover holding means operatively disposed in said end portion comprising a sleeve and means operatively mounted in said sleeve for supporting said cover; means depending from said cover by which said cover is mounted upon said means in said sleeve rotatably with respect to said seat; and means engaging said cover holding means, whereby said cover may

be moved in one direction only, namely, longitudinally of said end portion, into final closing position.

2. A ship ventilator closing and opening mechanism embodying a cover; an annular seat provided on the end portion of the ventilator coaming to which the closing and opening mechanism is applied; cover holding means operatively disposed in said end portion comprising a grooved sleeve and a worm; means depending from said cover by which said cover is mounted upon said worm rotatably with respect to said seat; and means engaging said cover holding means, whereby said cover may be moved in one direction only, namely, longitudinally of said end portion, into final closing position.

3. A ship ventilator closing and opening mechanism embodying a cover; an annular seat provided on the end portion of the ventilator coaming to which the closing and opening mechanism is applied; cover holding means operatively disposed in said end portion comprising a grooved sleeve and a worm; means slidably disposed in said cover and pivotally connected to and mounted upon said worm; and means engaging said slidably disposed cover means whereby said cover may be moved in one direction only, namely, longitudinally of said end portion, into final closing position.

4. A ship ventilator closing and opening mechanism embodying a cover; an annular seat provided on the end portion of the ventilator coaming to which the closing and opening mechanism is applied; means to maintain said cover in closed and open position consisting of a holding member secured in said end portion, a grooved sleeve supported by said holding member longitudinally of said end portion and a worm mounted in said sleeve and pivotally secured to said cover whereby said cover is secured in closed or open position upon said annular seat; means to hold said cover in desired tilted position; and means whereby said cover may be moved in one direction only, namely longitudinally of said end portion, into final closing position.

5. A ship ventilator closing and opening mechanism embodying a cover having a hole axially disposed therethrough and having two lugs depending from the under side of said cover; an annular seat provided on the end portion of the ventilator coaming to which the closing and opening mechanism is applied; and means to maintain said cover in closed and open position comprising a grooved sleeve arranged longitudinally of said end portion, a worm mounted in said sleeve, one end of said worm having a tongue disposed between said lugs depending from said cover, said tongue having a transverse opening therethrough, a clamping member extending through the axially disposed hole of said cover, the lower end of which clamping member is disposed in said transverse opening, a pin extending through said tongue and said lower end of said clamping member whereby the two are pivotally connected, a spring on said clamping means, and cam means to clamp said cover in closed position.

of said cover, the lower end of which clamping member is disposed in said transverse opening, a pin extending through said tongue and said lower end of said clamping member whereby the two are pivotally connected and means to clamp said cover in closed position.

6. A ship ventilator closing and opening mechanism embodying a cover having a hole axially disposed therethrough and having two lugs depending from the under side of said cover; an annular seat provided on the end portion of the ventilator coaming to which the closing and opening mechanism is applied; and means to maintain said cover in closed and open position comprising a grooved sleeve arranged longitudinally of said end portion, a worm mounted in said sleeve, one end of said worm having a tongue disposed between said lugs depending from said cover, said tongue having a transverse opening therethrough, a clamping member extending through the axially disposed hole of said cover, the lower end of which clamping member is disposed in said transverse opening, a pin extending through said tongue and said lower end of said clamping member whereby the two are pivotally connected and cam means to clamp said cover in closed position.

7. A ship ventilator closing and opening mechanism embodying a cover having a hole axially disposed therethrough and having two lugs depending from the under side of said cover; an annular seat provided on the end portion of the ventilator coaming to which the closing and opening mechanism is applied; and means to maintain said cover in closed and open position comprising, a grooved sleeve arranged longitudinally of said end portion, a worm mounted in said sleeve, one end of said worm having a tongue disposed between said lugs depending from said cover, said tongue having a transverse opening therethrough, a clamping member extending through the axially disposed hole of said cover, the lower end of which clamping member is disposed in said transverse opening, a pin extending through said tongue and said lower end of said clamping member whereby the two are pivotally connected, a spring on said clamping means, and cam means to clamp said cover in closed position.

8. A ship ventilator closing and opening mechanism embodying a cover; an annular seat provided on the end portion of the ventilator coaming, to which the closing and opening mechanism is applied; cover holding means operatively disposed in said end portion comprising a grooved sleeve and a worm connected to said cover operatively disposed in said sleeve; means whereby the screwing down movement of the cover is stopped at a predetermined point; and

means whereby said cover may be moved in one direction only, namely longitudinally of said end portion, into final closing position.

9. A ship ventilator closing and opening mechanism embodying a cover; an annular seat provided on the end portion of the ventilator coaming to which the closing and opening mechanism is applied; cover holding means operatively disposed in said end portion comprising a sleeve and means depending from said cover which engages with said sleeve; means whereby the movement of the cover in said sleeve is stopped at a predetermined point; and means whereby said cover may be moved in one direction only, namely longitudinally of said end portion, into final closing position.

10. A ship ventilator closing and opening

mechanism embodying a cover; an annular seat provided on the end portion of the ventilator coaming to which the closing and opening mechanism is applied; cover holding means operatively disposed in said end portion comprising a grooved sleeve and a worm pivotally connected to said cover operatively disposed in said sleeve; means whereby the screwing down movement of the cover is stopped at a predetermined point; and means whereby said cover may be moved in one direction only, namely longitudinally of said end portion, into final closing position.

In witness whereof, I hereunto subscribe my name this 27th day of October, A. D. 1921.

WILL H. BORROW.
